REED CONTACT SWITCHING UNIT HAVING RESILIENT STUD MEANS FOR SECURING COIL
Andreas Zerfass, Stuttgart-Weil im Dorf, Germany, assignor to International Standard Electric Corporation, New York, N.Y., a corporation of Delaware
Filed Sept. 15, 1964, Ser. No. 396,581
Claims priority, application Germany, Sept. 20, 1963, St 21,098
4 Claims. (Cl. 335—152)

This invention relates in general to reed relays and in particular to an arrangement of reed contacts for use in either normally open or normally closed relays wherein a permanent magnet is arranged juxtaposed to the contacts and the entire arrangement comprising the contacts and the magnet make up a replaceable modular unit.

There are reed contact relays known, equipped with a permanent magnet and which operate, depending on the intensity of the magnetism of the permanent magnet as non-operative or retentive relays. With these known arrangements the reed contacts and the permanent magnet are accommodated within the exciter coil and are encircled by said coil. Reed contacts and permanent magnet are inserted individually into the relay, fixed within the coil body and weakened to a certain magnetizing magnitude of the permanent magnet in an alternating field, together with the coil body. This arrangement, however, shows the considerable drawback that by the individual fixing of the reed contacts and of the permanent magnet the position of said permanent magnet to one or the other, or to all reed contacts used can be changed by mechanical shocks so that the once established values of the permanent magnet change, and consequently the pull-up and drop values of the reed contacts, in parallel to the permanent magnet, are outside the required tolerances.

Prior art arrangements show the permanent magnet and the reed contacts connected by a metal strip forming a sleeve, to glue the reed contacts in said sleeve-forming metal strip and by this connects them to a compact, replaceable component. This arrangement shows various advantages compared with the aforementioned design known, particularly with regard to combining the permanent magnet and the reed contacts into a replaceable component. It is shown that it is impossible to glue contact and magnet together, because the glass of the reed tube and the permanent magnet have so different heat expansion coefficients that it may occur that the reed tube shows cracks or the glueing is dissolved with the result that either the reed contacts become useless or due to the solution of the glueing the once set magnetic field intensity of the permanent magnet becomes useless for the entire component.

The object of the invention is to eliminate the disadvantages of the arrangement known. This is achieved, according to the invention, that the reed contact or contacts with the permanent magnet, producing a constant magnetic field, are enclosed in a poured resin block in such a way that, with consideration to maintain a small but defined distance of the individual components to each other, the terminal ends of the reed contact or contacts protrude from the finished resin block, and that the resin block is designed thus that on one side a firm stud and on the other side a movable or elastic stud is provided which can be bent back when inserting the thus formed component into a coil body and, after insertion is completed, engages in rear of a projection of the coil body, and thereby fixes the component in its longitudinal direction. The resin used for the component shows the temperature constancy of the coil body the permanent magnet thus surrounded by the resin will be set, depending

2

on the use either as a non-operative closed-circuit relay or a retentive relay, outside the coil body in an alternating field to a predetermined magnetic magnitude so that the pull-up and drop values of the reed contacts, enclosed together with the permanent magnet in the resin, remain within the tolerances required.

The invention shows the advantage that when using a certain resin the varying difference between the heat expansion coefficients of the individual elements are balanced.

- 10 By fixing the individual elements in one compact block a subsequent mechanical shifting and consequently a change of the magnetic values of said elements is impossible. Another large advantage is obtained from the elastic stud protruding from a part of the resin block
15 which fixes, in cooperation with the firm stud, the complete component within a coil body or in the longitudinal direction for a corresponding fitting within a coil, wound without a coil body.

Thereby all additional fixing means for the individual
20 elements or the entire component within the coil body can be omitted as compared with the arrangements known or proposed.

The invention is now in detail explained with the aid of the accompanying drawings, wherein:

25 FIG. 1 shows a component according to the invention, enclosed in resin, top view and in enlarged scale,

FIG. 2 shows a component according to FIG. 1, seen from the side,

30 FIG. 3 shows a component according to FIG. 1, seen from the front,

FIG. 4 shows a component according to FIG. 1, seen from the front side as per FIG. 3, inserted into a coil body.

35 FIG. 5 shows another example according to FIG. 1 in lateral view,

FIG. 6 shows a component as shown in FIG. 5, but seen from top,

FIG. 7 shows a component according to FIG. 5, seen from the front side, and

40 FIG. 8 shows a component according to FIG. 5 as represented per FIG. 7, inserted into a coil body.

FIG. 1 and the other figures show a resin block 1, called in the following paragraphs also a component. In said resin block reed contacts 2 and a permanent magnet 3 are accommodated in such a way that the terminals 4 and 5 of the reed contacts serving for connection protrude from said resin block. The component shows on one end a firm stud 8 and on the other end an elastic stud 6. Between the elastic stud 6 and the resin block 1 an elastic arm 7 is provided which is located between the grooves 11 and 12.

As may be gathered from FIG. 2 the component described in FIG. 1 is seen from the side in section, providing a hollow space 10 in rear of the elastic stud 6 into which said elastic stud 6 can be bent, when inserting the component into the coil body, shown in FIG. 4.

FIG. 3 shows the component from the front side whereby the individual elements, concentrated within the component are shown in dotted lines.

60 FIG. 4 shows the component as per FIG. 3, inserted into a coil body 9. As already described, the elastic stud 6 can be bent into the hollow space 10 of the resin block 1, when inserting into the coil body, and springs back after the edge 6" of said stud 6 engages in rear of the exterior portion of the flange of the coil body 9 or into a projection therefor provided. The component 1 inserted thus into the coil body is fixed within said body against shifting in longitudinal direction.

70 FIG. 5 and the other FIGS. 6 to 8 show a component 1' accommodating only one reed contact 2 and a permanent magnet 3. In this component 1' the terminals 4

and 5 of the reed contact 2 also protrude from the resin block. The component 1' shows only small differences compared with the component 1 and those parts showing such differences are marked with the same references as in the preceding FIGS. 1 to 4, but a prime has been added to said references. For example the firm stud of the component 1' is marked with 8' and the elastic stud with 6', the elastic arm with 7' and the space in rear of the elastic stud 6' with 10'. The indents rendering the elastic properties to the arm 7' of the component 1' are marked with 11' and 12'. Therefore no separate aspects arise for the description of FIGS. 6 and 7 compared with the description for the FIGS. 1 to 3, consequently no closer explanation of said FIGS. 6 and 7 is necessary.

FIG. 8 shows a component according to FIG. 5 inserted into a coil body 9'. The component 1' is not yet completely inserted into the coil body 9' so that the elastic stud 7' is shown bending into the hollow space 10'. When the unit 1 is completely inserted into the coil body 9 the stud 7' will be in a position indicated by a dotted line and marked 7".

The components 1 or 1' can also be inserted into a wound coil without coil body, when the external and internal dimensions of the coil are fitted to the components 1 or 1', respectively. It is also possible, in contrast to the explained and described examples, to combine more than two reed contacts with one or several permanent magnets to a component according to the invention, not particularly shown on the drawing.

While the principles of the invention have been described above in connection with specific apparatus and applications, it is to be understood that this description is made only by way of example and not as a limitation on the scope of the invention.

What is claimed is:

1. A reed relay assembly comprising a plurality of reed contacts contained in glass tubes, permanent magnet means arranged parallel to said tubes, resin block means for mounting said tubes and said permanent magnet in a juxtaposed, spaced apart relationship, terminals connected to said contacts and protruding from said resin block, reed relay operating coil means, said resin block having stud means for fixedly mounting said resin block in said coil, said stud means comprising a resilient stud on one end of said block and a firm stud on the other end of said block, and means on said coil for engaging said studs when said block is fully inserted in said coil.

2. In the relay assembly of claim 1 wherein said stud means comprises at least one resilient stud.

3. In the relay assembly of claim 2 wherein said resilient stud comprises a stud integrally mounted to a resilient arm.

4. In the relay assembly of claim 3 wherein said reed contacts are mounted parallel to one another with said permanent magnet arranged between said glass tubes and wherein said resilient stud means is also arranged between said glass tubes.
